SILENCER FOR COMBUSTION AND EX-
PLOSION ENGINES

Robert Pierre Pomiès, Paris, France

Application June 28, 1938, Serial No. 216,195
In France June 30, 1937

9 Claims. (Cl. 181—53)

In the known devices which are now used for decreasing the noise of the exhaust of engines, attempts have been made to deaden said noise by causing the burnt gases to pass through chambers having on the inside thereof baffles which are or are not combined with constrictions of cross-section.

This causes, in the majority of cases, either a loss of power, or an insufficient damping of the sound.

The applicant provides a complete solution of this technical problem; not only does he completely destroy the sound waves, but he obtains at the same time a considerable increase in the power of the engine.

In fact, in the means proposed by the applicant, any braking of the gases is avoided and the sound wave is separated from the gas which carries it.

In its general principle, the invention consists in arranging, in the path of the hot exhaust gases of an engine, at least one expansion chamber in which said gases are introduced or from which they are exhausted, through a port of reduced width but of sufficient cross-section to prevent braking, said port being located adjacent an outlet of gases from the chamber or an inlet into the latter, in such a manner that the oppositely directed gaseous inlet and outlet streams (the densities of which are different owing to the expansion and the cooling of the gases in the chamber) cause vortical zones opposite the port.

Said vortical zones are kept up by the flow in opposite directions, of the gaseous streams and the vortices have a high speed which is in principle greater than the speed of propagation of sound.

The vortical zone or zones thus created form a regular screen for the sound wave which is destroyed, and this is effected without braking the flow of the gases.

In this diagrammatical embodiment, the destruction of the sound wave is effected, on the one hand by the vortical movements, and on the other hand by the change of density of the gases in which the sound propagates.

To these two factors there may be added a third factor of destruction which enables an interference to be created by reflection of the sound wave.

The invention covers the combination, with the previously indicated means, of a second chamber which is arranged in opposition relatively to the first; said chambers, which are connected together axially by a pipe serving as an exhaust

from the first chamber and as an inlet into the second, enable, by the reflection of the sound wave on to the opposite ends of said chambers, an interference to be created in the pipe, the second chamber exhausting the gases into the atmosphere through a narrow port which, as in the first chamber and under the action of the two gaseous streams circulating in opposite directions, enables a second vortical zone to be formed.

In an industrial embodiment, the chambers which are in opposition, are mounted on the exhaust pipe and are placed in communication through a flattened pipe, said chambers being separated, outside the pipe, by a suitably inclined wall.

It is obviously possible to connect a plurality of devices in series, in parallel or in series-parallel.

20 In another embodiment with multiple chambers, the inclined wall is replaced by a cone provided radially and on the outside with flattened channels opening into chambers which are in principle evenly distributed along radii.

25 It is possible to combine two previously indicated systems in which the cones are in opposition, the interference being produced in the space limited by the cones.

30 It is also possible to connect a plurality of devices in series, in parallel or in series-parallel.

In another embodiment, the exhaust of each cylinder is effected through a nozzle which opens into a chamber, as indicated in the basic feature, the various chambers being connected together by a manifold made up of a plurality of elements.

35 The inlet or the outlet of the gases into the chamber or from the chamber, is effected through the intermediary of convergent or divergent walls.

40 The invention further covers other particular points which will become apparent from the ensuing specification taken with reference to the accompanying drawings which are only given by way of example and in which:

45 Fig. 1 is an explanatory diagrammatical view in section of a first embodiment of a silencer constructed according to the invention.

Fig. 2 is an elevation, in longitudinal section, 50 of an industrial embodiment, said section being taken on the left along the broken line II A. B. C. II of Fig. 3 and on the right along the straight line II—II of said figure.

Fig. 3 is a transverse section of the right hand 55 or left hand element of Fig. 2, said section being

taken in principle along the line III—III of said figure.

Fig. 3^a is a partial view of Fig. 3, but on a larger scale, in order to facilitate the illustration of a vortical zone.

Fig. 4 is an elevation, with a section taken along the line IV—IV of Fig. 5 and showing another industrial embodiment.

Fig. 5 is a section taken along the line V—V of Fig. 4.

Fig. 6 is a sectional elevation of a modification.

Fig. 7 is a section taken along the line VII—VII of the previous figure.

Fig. 8 illustrates in section, an embodiment provided with a device for the exhaust of each cylinder.

In the embodiment illustrated diagrammatically in Fig. 1, the exhaust gases penetrate into the silencer through the pipe 1, in the direction of the arrow F^a. The cross-section of the pipe 1 is amply calculated so as not to produce any braking of the stream issuing from the manifold. Said pipe 1 communicates, through an annular port 3, with a chamber 4 into which a tube 5 opens co-axially with the annular port 3.

The exhaust gases penetrating by means of the pipe 1 into the chamber 4 through the annular space 3, are cooled in said chamber; a balance of pressure is instantly set up and the gases escape through the conduit 3 in the direction of the arrow F^a.

The elementary apparatus could be limited to the main parts which were previously indicated.

By suitably arranging the annular port 3 and the inlet 5^a relatively to each other, a very rapid toric vortical zone 7 is set up between the stream which enters the chamber 4 (hot gases of low density) and the stream issuing from said chamber 4 (cooled gases of greater density). This vortical movement 7 is produced by the friction of the two gaseous streams of different densities circulating in opposite directions.

The annular port 3 is of relatively small width but of sufficient diameter to prevent in principle any braking of the gases which thus flow in a thin annular sheet. Said sheet is, furthermore, reduced owing to the creation of the vortical torus 7 which by its movement facilitates the inlet of the gases into the chamber 4.

The sound wave is partially or totally destroyed by the vortices which, in the zone 7, have a very high speed which is in principle higher than the speed of sound. Furthermore, the destruction of the sound wave is partially effected by the change of density of the gases in which the sound propagates. Thus the separation is effected, on the one hand of the sound wave which is destroyed, and on the other hand of the exhaust gases which carry said sound wave.

Independently of the two destructive effects on the sound wave, as has just been indicated, an interference can be created by reflection of sound in order to completely destroy the sound wave before it reaches the outlet of the silencer.

Such an embodiment is shown in Fig. 1 in which the outlet 5^b of the pipe 5 opens into a second chamber 8 which communicates with an exhaust pipe 9 through an annular port 10.

Owing to the relative arrangement of the outlet 5^b and of the port 10, a second vortical zone 11 is produced which also destroys the sound wave.

It will be observed that with such an arrangement, another destructive phenomenon for the sound wave is involved if care is taken to ar-

range suitably the chambers 4, 8 and the pipe 5.

In fact, the sound wave is reflected on to the opposite walls 4^a and 8^a of the chambers 4 and 8 which are arranged in opposition but are connected together axially by the pipe 5. An interference is produced inside said pipe 5 and, at the outlet of the pipe 5, only an extremely small noise is perceived which is moreover drowned, as shown by the applicant's tests, by the mechanical noises of the engine.

It is moreover possible, in the case of a high speed engine operating with high compression, to multiply the number of apparatus and to make a series, or parallel, or series parallel connection.

Industrial embodiments of a silencer will now be described which involve the principles and the phenomena previously indicated with reference to Fig. 1.

In the embodiment which will be described hereinafter, in order to obtain the maximum speed of the vortical movement, the orifices of the various chambers have been so constructed as to form nozzles of the Venturi type.

Figs. 2, 3 and 3^a illustrate an embodiment in which the chambers 4 and 8 are mounted on the exhaust tube 11 itself of the engine, two elements being connected in series. The two chambers 4 and 8 of each element are in communication with each other, through a flattened pipe 5 and are separated, at the outside of said pipe, by an inclined wall 12.

The hot gases which arrive through the pipe 1 (arrow F^a) flow into the chamber 4 through the two ports 3 formed by the walls of the chamber 4 and the end of the inlet 5^a of the tube 5. The gases then flow in the direction of the arrows and through the flattened pipe 5, into the chamber 8 and thence, through the ports 10, towards the channel 9^a.

A second path, which is identical with the first, is effected in the second element, the gases finally issuing through the pipe 9^b.

It will be observed that the circulation of the gases in each element is effected in an identical manner with that described with reference to Fig. 1. Vortical zones are respectively formed opposite the ports 3 and 10 and an interference is produced in each flattened pipe 5.

In order to increase the speed of the vortices, the walls of the chambers, adjacent the ends 5^a and 5^b of the pipe 5, are inclined to form convergent and divergent surfaces 14 and 15 which produce an expansion and a cooling.

Each oblique partition 12 is arranged in such a manner that the increasing constriction of the tube is compensated by the lateral openings 3.

In the chamber 4, the gases which arrive as shown about the pipe 5 and through the ports 3, tend to return to said chamber the cooled gases which flow through the pipe 5 towards the chamber 8; this part of the apparatus operates as an ejector.

In the chamber 8, on the contrary, the gases which arrive through the pipe 5 tend to re-inject the cooled gases into said chamber 8 and which escape through the ports 10; this part of the apparatus operates as an injector.

In order to obtain the maximum friction between the gaseous streams which enter and issue from each chamber, for the purpose of increasing the speed of the vortices of the vortical zones, it is preferable to place the outlet of the venturi 14 slightly back from the inlet 5^a, and the inlet 5^b back from the inlet of the venturi 15.

In the chamber 4, the system operates, as in-

dicated, as an ejector, and in the chamber 8 as an injector.

Figs. 4 and 5 illustrate an embodiment of a silencer having eight chambers 4, the oblique partition 12 of the previous example being replaced by a cone 12^a placed inside the exhaust tube. The inner part of the cone is placed in communication with each chamber 4 through radial pipes 5, convergent walls being provided at 14.

The gases which arrive through the pipe flow simultaneously between the pipes 5, into the various chambers 4, through the ports 3. The cooled gases then flow from each chamber, through the pipes 5, into the cone 12 whence they are exhausted through the tube 5^a.

Opposite the ports 3 and 10, vortical zones are produced, the vortices of which have a high speed.

In the embodiment of Figs. 4 and 5, each part operates as indicated with reference to the elements 1, 4 and 3 of Fig. 1, the chambers not being placed in opposition.

Figs. 6 and 7 illustrate a modification of the embodiment shown in Figs. 4, 5. In this example, two units are used arranged end to end. The left hand unit is identical with the device of Figs. 4 and 5. Under these conditions, the gases which issue from the first unit through the pipe 5^a, flow into the cone 12^b placed in opposition to the cone 12^a. The gases are then directed through radial pipes 5, into the chambers 4, whence they flow, through the ports 10, between the pipes 5 and finally into the atmosphere through the pipe 9^c, divergent walls being provided at 15.

The second element (the right hand one) operates as indicated with reference to the parts 5, 8 and 9 of Fig. 1. However, in this embodiment, an interference of the sound waves is caused in the space formed by the two cones 12^a—12^b and the pipe 3^a.

In the examples of Figs. 4 to 7, the cutting up of the sound wave is effected. The various radial parts behave like a single chamber.

It has been observed that, if a silencer according to the invention is mounted on a fixed engine, or an automobile engine, a perfect silence is always obtained at the exhaust.

In the case of an aeroplane engine, the problem becomes complicated, since although the silencing devices operate with the same efficiency, it is found that the manifolds supplied with the engines are far from being as insonorous as those of automobile engines owing to the fact that the first are generally made of special alloys and constructed with thin walls, whereas the second are stronger and are made of cast iron for example.

In practice, in aeroplane engines, although an absolute silence is obtained at the exhaust with the device according to the invention, the walls of the exhaust manifold vibrate and go into resonance with the noise of the individual explosions of each cylinder.

In order to give a complete solution in each particular case, it is necessary to complete the silencer by a special construction of the manifold.

In order to facilitate the explanation of the complete solution proposed by the applicant, a simple straight engine 20 has been shown in Fig. 8. The cylinders 21, 22, 23 and 24 are each provided, at the exhaust, with a nozzle 5^r which opens into a chamber 8. The operation of each system 5^r—8 is comparable to that indicated with reference to the parts 5, 8 and 9 of Fig. 1, a ven-

turi being provided in each chamber at 15. The vortical movements take place in each chamber opposite the ports 10. The various systems are mounted on a common manifold 9 formed by tubular parts 9^t connecting the various systems together.

In this embodiment, not only is the benefit obtained of the destruction of the sound wave at the actual source where it is perceptible, but the resonance of a thin walled manifold is stopped owing to the formation of the manifold by a plurality of elements acting to transfer the natural frequency of vibration of the manifold outside the audible frequencies.

The different embodiments previously described not only enable the sound wave to be completely destroyed, but also the power of the engine to be increased.

As the braking of the flow of the gases in the silencer is practically nil, the silencer according to the invention does not cause any loss of power. But, owing to the expansion of the gases and their cooling in the chambers, a regular contraction of said gases occurs and consequently a suction effect of the gases issuing from the engine.

When they issue from the silencer, the gases are at a temperature of the order of 30 degrees C. and the gain of power observed during tests attained 11.8 per cent.

It is obvious that the embodiments described and illustrated are only given herein by way of an indication and are non-limitative. Any modifications or variations which, in no way change the main features hereinbefore explained, or the object aimed at, remain included in the scope of the present invention.

What I claim as my invention and desire to secure by Letters Patent is:

1. In a silencer for an internal combustion engine or the like, a casing forming a gas expansion chamber having opposite end walls, an inlet port located in one end wall and an outlet port located in the other end wall, said inlet and outlet ports determining a longitudinal axis in said silencer, a concave bottom forming a downward extension below said axis in said casing, an upward extension above said axis forming a concave top in said casing opposite said concave bottom, separation means separating one port and the concave top, on the one hand, from the other port and concave bottom, on the other hand, and means including a pipe extending transversely of said axis and connecting the interior of the casing within said concave top with the interior of said casing within said concave bottom through said separation means, there being means for connecting the inlet port with an exhaust pipe of said engine.

2. In a silencer for an internal combustion engine or the like, a casing forming a gas expansion chamber having opposite end walls, an inlet port located in an intermediate portion of one end wall and an outlet port located in an intermediate portion of the other end wall, said inlet and outlet ports determining a longitudinal axis in said silencer, a concave bottom forming a downward extension below said axis in said casing, an upward extension above said axis forming a concave top in said casing opposite said concave bottom, separation means separating one port and the concave top, on the one hand, from the other port and concave bottom, on the other hand, and means including a pipe extending transversely of said axis and connecting the

interior of the casing within said concave top with the interior of said casing within said concave bottom through said separation means, there being means for connecting the inlet port with an exhaust pipe of said engine.

3. A silencer according to claim 1, in which the inlet port has an opening larger than the exhaust pipe of the engine from which the exhaust gases are introduced into the inlet port.

4. A silencer according to claim 1, in which the separation means includes an inclined partition which is inclined from the upper portion of the inlet port down toward the lower portion of the outlet port.

5. A silencer according to claim 1, in which a plurality of casings are connected in series with the outlet port of one casing connected to the inlet port of the next adjacent casing.

6. A silencer according to claim 1, in which the casing is of greater dimensions vertically and longitudinally or horizontally than transversely, while the pipe connecting the interiors within the concave top and bottom of the casing extends substantially vertically and constitutes a flat pipe of greater dimension in the direction of the axis of the silencer than transversely of said axis.

7. A silencer according to claim 1, in which a plurality of casings are connected in series with the outlet port of one casing connected to the inlet port of the next adjacent casing, while having the inlet port in each casing larger than the outlet port of the next preceding casing, and wherein the concave bottom includes a chamber below the composite axis of the series and the separation means includes a bottom wall in the main portions of the case, and an upper wall in said lower chamber and a pipe in each case constitutes a nozzle connecting said lower chamber through said upper wall thereof and the lower wall of the main portion of the casing and also extending upwardly toward the interior of the concave top in each case.

8. A silencer according to claim 2, in which the casing has a plurality of additional extensions in the form of concave portions resembling the concave top and bottom and extending in a plurality of directions transverse of the axis so that a transverse section of all said extensions present a certain formation, and the pipe is similarly provided with additional branches extending individually toward the interiors of said extensions or concave portions, while one portion of said pipe at one end of the casing is open so as to connect fully with the outlet port of the casing, the individual branches of the resulting star-shaped pipe structure forming the connections between said extensions, while other portions of said pipe structure intermediate said branches constitute the separation means.

9. A silencer according to claim 2, in which at least two casings are arranged in a series and each casing has a plurality of additional extensions in the form of concave portions resembling the concave top and bottom and extending in a plurality of directions transverse of the axis so that a transverse section of all said extensions present a certain formation, and the pipe is similarly provided with additional branches extending individually toward the interiors of said extensions or concave portions, while one portion of said pipe at one end of the casing is open so as to connect fully with the outlet port of one casing, the individual branches of the resulting star-shaped pipe structure forming the connections between said extensions, while other portions of said pipe structure intermediate said branches constitute the separation means in each casing, while the pipe in the second or successive casing opens fully to occupy the inlet port of said second casing and connects with the outlet port of the first or preceding casing.

ROBERT PIERRE POMIÈS.
